UNITED STATES PATENT OFFICE.

FRANK TATAR, OF NEW YORK, N. Y.

SHOCK-ABSORBER.

1,331,885.

Specification of Letters Patent. Patented Feb. 24, 1920.

Application filed May 20, 1919. Serial No. 298,490.

To all whom it may concern:

Be it known that I, FRANK TATAR, a citizen of Hungary, residing at New York city, in the county of New York and State of 5 New York, have invented new and useful Improvements in Shock-Absorbers, of which the following is a specification.

My invention relates to means for use in vibratile buildings, and in connection with 10 drop-hammers and like apparatus having a hammer-action.

Owing to the safety ordinances and building regulations in force in modern cities and communities, the operation of drop-hammers and similar apparatus is forbidden 15 in buildings, which, by reason of their construction, condition or age, are comparatively and injuriously responsive to sharp and heavy blows.

20 My invention, therefore, has as its paramount object the provision of a simple and efficient structure, on which to cushion the parts receiving the blows, so that the shocks and vibrations incident to the blows will be taken up and absorbed to a large extent instead of being communicated directly to the building.

With the foregoing and other objects in view, the invention resides in the details of 30 construction and in the arrangement and combination of parts as hereinafter described, defined in the annexed claims, and illustrated in the accompanying drawings, in which is shown the preferred embodiment 35 of the invention as reduced to practice, and in which:—

Figure 1 is a top plan view of my improved structure.

Fig. 2 is a side elevational view with parts 40 in section, showing the structure as supported upon the building floor, and as cushioning the anvil portion of a drop-hammer, herein shown in broken lines.

With more particular reference to the 45 accompanying drawings, the numeral 5 is employed to denote floor-joists, which are supported in the usual way by the building beams or girders as 6, and which support in the usual way the flooring 7.

Placed upon the flooring and rigidly secured thereto, and as well to the floor-joists or beams accordingly as conditions require, by any suitable means for instance by screws 50 as 8, are spaced parallel sills 9 and 10. Arranged in spaced parallel relation upon these sills and secured thereto, for instance, by

spikes as 11, are the bolsters 12 and 13. Working through bores 14 provided for the purpose in the bolsters 12 and 13 are plunger-bolts 15, of which, in the present embodiment of the invention, there are four in number. Upon the heads 16 of these plunger-bolts, underneath the bolsters, are supported the planks or other suitable horizontal members 17 and 18, it being noted that 60 the plunger-bolts are preferably located in such alined positions that the planks 17 and 18 come between the sills 9 and 10 with which they are parallel, and also between the bolsters 12 and 13, whose planes they 65 traverse, and the flooring.

Cut in the top sides of the bolsters, concentric with the bores 14, are circular cavities or seats 19, in which rest the lower ends of the coil or cylindrical springs 20, which 70 surround the plunger-bolts as shown. Upon the top ends of each pair of springs, thus rising from each bolster, is a plate 21, provided with suitable openings 22 to permit the top extremities of the plunger-bolts to 75 project therethrough. Surrounding the plunger-bolts, above the plates 21 are strong washer-disks 23, and over these are screw-threaded upon the plunger-bolts the nuts 24. By this arrangement, it will be readily seen, 80 that the planks 17 and 18, although located below the bolsters, are nevertheless cushioned upon the same, so that the vibrations incident to the striking of vigorous and heavy blows upon the planks or upon an 85 object supported thereon, will be taken up and absorbed by the springs to a large extent, instead of being communicated directly to the flooring, joists and beams, of the building.

As shown in the accompanying drawings, 90 the anvil 25 of the hammer machine is placed or secured upon the planks 17 and 18 in a central position with respect to the plungers and springs, so that its weight may be 95 equally distributed thereon. The articles to 100 be hammered, shaped or forged, are placed or supported upon the anvil in any customary manner, in position to be properly operated upon by the hammer 26 under its descending strokes. Under each blow struck 105 by the hammer, the planks and plungers descend uniformly toward the flooring, compressing the springs, which absorb the force of the blow and as well the vibrations resulting therefrom.

In buildings, wherein drop hammers and similar apparatus have heretofore been for-

bidden to operate, the same are now permitted to operate when used in conjunction with my improved shock-absorbing structure, it having been ascertained by tests satisfactory to the building inspectors, that the blows of the hammer no longer have serious vibratory effects on the building.

Having thus described my invention, what I claim is:—

- 10 1. A shock-absorbing structure for use in buildings and on which an anvil or similar device may be supported, including bolsters and means for supporting them in spaced parallel relation above the building floor, 15 coil-springs seated in and rising from said bolsters, plunger devices extending vertically through said bolsters and forming the axes of said springs, means on the top ends of the plunger devices and resting on the top 20 ends of the springs whereby resiliently to support the plunger devices on the springs, and means supported by and between the plunger devices below the bolsters for carrying an anvil or similar device.
- 25 2. In a device of the character described, spaced parallel sills, a pair of bolsters secured upon and crossing the sills in spaced parallel relation, said bolsters being provided with vertical bores opening into concentric cavities, coil springs seated in said 30 cavities and rising from said bolsters, plunger devices extending through said bores and forming axes for said springs, connections between the plunger devices of each 35 bolster resting upon the top ends of the springs, means associated with the top ends of the plunger devices for holding said connections in position upon the springs whereby the plunger devices are resiliently cushioned, and means supported by and between the plunger devices below the bolsters for carrying an anvil or similar device, as and 40 for the purpose specified.

3. In a device of the character described,

the combination with a pair of bolsters and 45 means for rigidly supporting them in spaced parallel relation, coil-springs seated in and rising from the bolsters in vertical parallel planes which come between the planes of the bolster supports, plunger devices extending 50 upwardly through said bolsters and forming axes for the springs, means on the top ends of the plunger devices and resting on the top ends of the springs whereby resiliently to support the plunger devices on the springs, 55 and means supported by and between the plunger devices below the bolsters for carrying an anvil device whereby when a blow is struck upon the anvil the same may have bodily movement relatively with respect to 60 the bolsters.

4. In a device of the character described, the combination of a flooring, sills secured to the flooring in spaced parallel relation, bolsters secured upon and crossing the sills 65 in spaced parallel relation, said bolsters being provided in parallel planes between the sills with vertical bores opening into concentric cavities, coil-springs seated in said cavities and rising from the bolsters, plunger 70 devices extending upwardly through the bores and forming axes for the springs, means on the top ends of the plunger devices and resting on the top ends of the springs whereby resiliently to support the plunger 75 devices on the springs, connections between the top ends of the bolsters, and means supported by and between the plunger devices below the bolsters for carrying an anvil device whereby when a blow is struck upon the 80 anvil the same may have relative bodily movement to prevent the flooring from sustaining the force of the blow and the resultant vibrations.

In testimony whereof I have signed my 85 name to this specification.

FRANK TATAR.
